UNITED STATES PATENT OFFICE

2,069,072

MATTRESS COVER AND METHOD OF
MAKING THE SAMEJames Reid Johnson, New London, Conn., as-
signor to The Palmer Brothers Company, New
London, Conn., a corporation of Connecticut

Application March 1, 1935, Serial No. 8,789

7 Claims. (Cl. 41—17)

My invention relates to the exterior facing or cover of a mattress, for instance of the class wherein a resilient core is inserted within a padded casing to form an unitary assembly.

Objects of my invention are to form such a facing or cover of a number of pieces cut from a strip of textile material or fabric with a minimum of waste, to assemble these pieces to produce a facing of the proper proportions and of a symmetrical, ornamental, panel like design differing from the design of the strip of material; to employ for the strip of material a repeating design embodying certain fixed relations between its repeating unit and the width of the strip and the dimensions of the facing; to produce from the original strip of material a plurality of panel-like designs in the finished facings; to accomplish the desired results by employing a novel system of ornamentation for the strip of material, and a peculiar method of cutting it into pieces for reassembling in ultimate form; and to secure the other advantages hereinafter pointed out and claimed.

Because of the size and shape of bedding mattresses it is desirable to apply to their broad faces ornamentation which will make them attractive to the eye of the housewife or user, and, in order to avoid monotonous repetition, ornamentation having the satisfying qualities of a complete, closed design, for instance, a panel, is found to be suitable.

To produce such panels by jacquard weaving is such a slow and expensive process as to make the resulting product entirely too costly for any general use; and to make them by roll printing requires that the design for the entire length and width of the mattress must be engraved upon a single printing roll which must be of a circumference equal to the length of the design, plus the necessary leeway between the several imprints and of a length exceeding the width of the mattress. The production of such printing rolls and their operation is altogether too tedious and expensive for the successful commercial production of the desired facing panels. But by the use of the method which I employ very satisfactory results may be obtained.

In the drawing, Fig. 1 shows a strip of fabric bearing certain systems of ornamentation thereupon; Fig. 2 shows a panel-like assembly of pieces cut from said strip, on broken lines for instance as suggested in the drawing, but not on the strip itself, to form a closed design; Fig. 3 shows another panel-like assembly of other pieces, also cut from said strip on broken lines,

the design, however, being reversed; Fig. 4 is a view, on an enlarged scale, of half of a panel of the type of Fig. 2.

The strip 1 is of a suitable fabric, and is shown as being of one half the width of the proposed facing panel. For instance this strip may be thirty inches wide. It is shown as being provided with three systems of ornamentation, borders 2, 3 and medial stripe 4. These borders and stripe are formed of rather definitely spaced, repeating figures having a predetermined relation to the width of the strip. For instance, if the strip is 30 inches wide each of the design figures shown in the borders and stripe will be 6 inches long, as they are shown as repeating five times in the width of the strip.

The designs of the borders of the strip as shown are complementary to each other; and it is desirable to maintain this same relationship in the assembled panel. To do this, however, it is necessary to cut the fabric in a certain particular way.

In cutting the fabric it is necessary to take into account that a mattress has the shape of a rectangular oblong, the length of which is greater than the width.

Starting at or near one end of the fabric it is cut across diagonally at an angle of 45 degrees, as on broken line 5 of Fig. 1, preferably severing the figures of the design midway. A distance 6, equal to the desired difference between the length and width of the panel, is then measured off on the margin 3 of the strip, this distance measuring a definite number of ornamental units, for instance, in the illustrations, two. The fabric is then cut in the reverse direction to the former cut, and again at an angle of 45 degrees, as on line 7, Fig. 1. This gives a piece of fabric 11. And similar pieces 12, 13 and 14 may then be cut from the strip. Triangular pieces 15, 16, 17 and 18 may then be cut from the strip. This will give eight pieces of fabric. Alternate pieces are then assembled into two panels, 11, 13, 15 and 17 into one panel, as in Fig. 2; and 12, 14, 16 and 18 into another panel as in Fig. 3.

This method of cutting and assembling produces, without waste of material, except by the original diagonal cut, two different panel patterns. For it will be noted that in Fig. 2 the trend of the pattern figure is uniformly in one direction, while in the Fig. 3 the trend is reversed. It is important to have this uniformity of trend in any panel, in order to preserve symmetry of design and to permit the elements of the designs, severed by the diagonal cutting lines, to register harmoniously with each other when the

pieces are assembled together. In that assembling, if the adjacent pieces are faced against each other and sewed along their joining edges, the symmetry of the design will not be destroyed; 5 for it will simply be shortened equally on the edges of each piece and a proper balance will be retained.

The cutting of the pieces need not proceed in the identical order described above, as triangular pieces may be severed from between longer pieces so long as a properly balanced number of each is obtained, and the assembling of each 10 panel is done with alternate pieces.

While, for the best practice of my invention it is important that the length of the unitary repeat 15 design should be carefully regarded, yet the particular form of ornamentation may be varied at will, the types shown on the drawing being simple forms illustrating, diagrammatically, the principles 20 of my invention.

My improvements enable me to use printing rolls of small diameter, for instance, of four to 25 six inches, and only half the width of the panel in length, for instance, 30 inches, which effects a great saving in the production of the rolls and 30 printing and engraving cost. Nothing need be allowed on the rolls for leeway or skip between the panel designs. The design is continuously 35 repeated, and it may be cut as directed, without 40 any intermediate waste.

By means of my improvements I am enabled to produce well balanced, symmetrical, panel- 45 designs from reassembled portions of a strip of material having continuous, ornamental designs 50 thereupon, at greatly reduced labor and expense and with most pleasing effects, mattress facings, made as above, appealing to the buying public, and giving continuing satisfaction to purchasers 55 and users.

40 By using rolls of the reduced sizes above suggested with a standard printing machine I am enabled to print as high as sixteen colors to a pattern at one operation, and still secure the desired panel effect for a full sized mattress. This would 45 be quite impracticable if the result was attempted with rolls of sufficient diameter to print a complete panel at each revolution, as but a small number of such rolls could operate in cooperation with a cylinder platen of practicable size. These 50 advantages will be obvious to anyone familiar with the printing art.

Having thus described my invention what I claim and desire to secure by Letters Patent of the United States, is:

55 1. The method of making an ornamental mattress facing consisting of producing a textile strip of half the width of the facing, having along each edge a continuous repetition of similar, uniformly spaced design units of curved and irregular lines 60 each divisible evenly into the length and width of the facing, cutting the strip diagonally at angles of forty five degrees into two right angled triangles and two sections having oppositely inclined ends and longer than the base of each triangle by the 65 length of one or more of said design units, assembling the two elongated pieces with their short sides adjoining, filling the spaces between the ends of the elongated pieces with the triangular pieces, and securing the pieces in assembled relations, whereby the ornamental elements are 70 formed into a balanced, closed panel design with a continuous border of substantially uniform pattern.

2. The method of making an ornamental mattress facing consisting of producing a textile strip 75

of half the width of the facing, having along each edge a continuous repetition of design units of a distinctive pattern each unit being divisible evenly into the length and width of the facing, and embodying curved and irregular lines, the patterns of the units being similar but reversed on the opposite edges, cutting the strip diagonally at angles of forty five degrees into two right angled triangles and two sections having oppositely inclined ends and longer than the base of each triangle by the length of one or more of said design units, assembling the two elongated pieces with their short sides adjoining, filling the spaces between the ends of the elongated pieces with the triangular pieces, and securing the pieces in assembled relation, whereby the ornamental elements are formed into a balanced, closed panel design with a continuous border of substantially uniform pattern. 5

3. The method of making an ornamental mat- 20 tress facing consisting of producing a textile strip of half the width of the facing, having thereupon a continuous repetition of uniformly spaced design units of distinctive pattern embodying curved and irregular lines, along each 25 edge, and another repetition of uniformly spaced design units of distinctive pattern and embodying curved and irregular lines midway of the strip, each design unit being divisible evenly into the length and width of the facing, cutting the 30 strip diagonally at angles of forty five degrees into two right angled triangles and two sections having oppositely inclined ends and longer than the base of each triangle by the length of one or more of said design units, assembling the two 35 elongated pieces with their short sides adjoining, filling the spaces between the ends of the elongated pieces with the triangular pieces, and securing the pieces in assembled relations, whereby the ornamental elements are formed in- 40 to a balanced, closed panel design with a continuous border of a substantially uniform pattern. 40

4. The method of making ornamental mat- 45 tress facings, consisting of producing a textile strip of half the width of the facing and having thereupon a continuous repetition of uniformly spaced complementary design units of a distinctive pattern and similar longitudinal trends along 50 each edge, each unit being evenly divisible into the length and width of the facing, cutting the strip diagonally at 45 degree angles into four relatively reversed right angled triangles and four relatively reversed elongated pieces with 55 oppositely inclined ends and with sides evenly divisible by the design units, assembling two alternate, elongated pieces and two alternate triangles into a complete, closed panel design the ornamentation of which has a continuous design trend, and assembling the other elongated 60 pieces and triangles into another closed panel design having a relatively reversed, continuous design trend. 65

5. The method of making ornamental mat- 70 tress facings, consisting of producing a textile strip of half the width of the facing and having thereupon a continuous repetition of complementary design units of distinctive pattern and definite trend along each edge, and an intermediate, continuous repetition of design units 75 of distinctive pattern, each unit being evenly divisible into the length and width of the facing, cutting the strip diagonally at 45 degree angles into four relatively reversed right angled triangles and four relatively reversed elongated 80

- pieces with oppositely inclined ends and with sides evenly divisible by the design units, assembling two alternate, elongated pieces and two alternate triangles into a complete, closed panel
- 5 design the ornamentation of which has a continuous design trend, and assembling the other elongated pieces and triangles into another closed panel design having a relatively reversed continuous design trend.
- 10 6. An ornamental, rectangular, oblong mat-tress facing embodying in assembled relation two relatively reversed elongated sections and two relatively reversed right angled triangles, the ornamentation exemplifying a continuous even repetition of marginal design units having a uniform and relatively reversed trend, and a con-
- 15 tinuous even repetition of central design units having a uniform and relatively reversed trend.

7. An ornamental, rectangular, oblong mat-tress facing embodying in assembled relation two relatively reversed elongated sections and two relatively reversed right angled triangles, the ornamentation exemplifying a continuous even repetition of marginal design units embodying curved and irregular elements having a uniform trend, and a continuous even repetition of central design units embodying curved and irregular elements having a uniform trend, and a continuous even repetition of intermediate design units embodying curved and irregular elements having a uniform trend.
